UNITED STATES PATENT OFFICE.

BRIDGES SMITH, OF MACON, GEORGIA.

RAILROAD-TIE.

SPECIFICATION forming part of Letters Patent No. 451,295, dated April 28, 1891.

Application filed July 7, 1890. Serial No. 357,975. (No model.)

To all whom it may concern:

Be it known that I, BRIDGES SMITH, of Ma-
con, in the county of Bibb and State of
Georgia, have invented a new and Improved
5 Railroad-Tie, of which the following is a full,
clear, and exact description.

My invention relates to improvements in
railroad-ties; and the object of my invention
is to produce a metal tie that will be strong
10 and durable, that will be simple and cheap,
that will be self-ballasted, that will possess
the necessary amount of elasticity, that may
be easily and rigidly fastened in the soil, and
that will have means for easily securing the
15 rail thereto.

My invention consists in certain details of
construction which will be hereinafter fully
described and claimed.

Reference is to be had to the accompanying
20 drawings, forming a part of this specification,
in which similar letters of reference indicate
corresponding parts in all the figures.

Figure 1 is a perspective view of the tie
embodiment my invention. Fig. 2 is a dia-
25 gram of the blank from which the tie is
formed. Fig. 3 is a broken perspective view
of the plate which is inserted in the tie when
water is to run through the same.

The tie A is formed from a sheet-metal
30 blank B, which is cut inwardly diagonally at
its edges on the lines d' to produce the points
d, as shown in Fig. 2. The blank is then
bent on the lines b, and the bent-down parts
A' are bent inwardly on the lines b' between
35 the points d, so that the edges b² of the blank
meet but do not lap, forming a mainly rect-
angular body having the downwardly-ex-
tending points d, as shown in Fig. 1. By
forming the tie in this manner there will be
40 a small amount of elasticity to it, thereby
overcoming the objection to many forms of
metal ties that they are too rigid. The tie is
provided on its upper side with holes f, there
being a pair of said holes near each end of
45 the tie, and the holes are a sufficient distance

apart to allow an ordinary rail to rest between
them, and the rail may be attached to the tie
by bolts extending through the holes f or by
any desired form of fastening.

When the tie A is laid in the soil, it may be 50
filled with earth, clay, or other suitable ma-
terial, thus affording ballast for the tie and
keeping it rigidly in place. If the tie is laid
in a water-gap or in a place where water is
liable to find an outlet through the railroad 55
embankment, the filling may be omitted from
the tie and a plate C inserted therein, said
plate being adapted to fit closely in the bot-
tom of the tie and having upwardly-turned
edges c, adapted to cover the apertures caused 60
by cutting the points d from the blank B, and
the water will flow through the tie. It will
thus be seen that the water will be conducted
away from the road without injury thereto.
The tie is made preferably of sheet metal, 65

which may be easily shaped, and from the
foregoing description it will be readily seen

that the tie is extremely cheap, that it may
be very easily applied, and when once in
place will remain firmly in position. 70

Having thus described my invention, I
claim as new and desire to secure by Letters
Patent—

1. As a new article of manufacture, a hol-
low metallic railroad-tie made from a sheet- 75
metal blank having diagonal cuts in its edges
and bent to form a hollow rectangular body
having depending points, substantially as
shown and described.

2. The combination, with a hollow rectan- 80
gular railroad-tie formed in a single piece with
meeting edges at the bottom, of a plate
adapted to fit closely in the bottom of the tie,
substantially as described, and for the pur-
pose set forth.

BRIDGES SMITH.
